UNITED STATES PATENT OFFICE.

CYRUS W. BALDWIN, OF CHICAGO, ILLINOIS, ASSIGNOR TO WILLIAM E. HALE, OF SAME PLACE.

GAS-ENGINE.

SPECIFICATION forming part of Letters Patent No. 276,751, dated May 1, 1883.

Application filed December 13, 1882. (No model.)

To all whom it may concern:

Be it known that I, CYRUS W. BALDWIN, of Chicago, Cook county, Illinois, have invented certain Improvements in Gas-Engines, of which 5 the following is a specification.

My invention relates to engines which are constructed to be operated by the expansion of ignited gases; and it consists in constructing the same to explode the charge of gases in 10 contact with a volume of non-explosive gas which acts as a cushion, and in certain details of construction fully set forth hereinafter.

In the drawings, Figure 1 is an elevation in part section of a double-action gas-engine 15 illustrating my invention. Fig. 2 is a plan in part section of Fig. 1. Fig. 3 is an enlarged cross-section on the line 1 2, Fig. 2. Fig. 4 is an enlarged cross-section on the line 3 4, Fig. 2, and Fig. 5 is an enlarged detached section 20 of the inlet-valve.

There is an explosion-cylinder, A, and compression-cylinder B, for which latter a reservoir and valve to admit gases therefrom may be substituted in some cases. The explosion-cylinder as shown is for a double-action engine, and is contracted at each end to form a central chamber, E, receiving the piston D, and end chambers, F F', for receiving the plunger-extensions d d' of the piston. The 25 piston, plungers, and piston-rod Q are hollow, and the opposite ends of the piston-rod extend into cylinders W W', the latter communicating through a pipe, 18, having a check-valve, 19, with a water-supply, and the former communicating through a pipe, S', having a check-valve, 20, with the water-chamber T, surrounding the cylinder. A pipe, U, extends from the chamber T. As the piston reciprocates the water is drawn into the cylinder W, then forced 30 through the piston-rod and piston into the cylinder W' and into and out of the chamber T. This effects the elevation or movement of the water for any desired purpose and serves as a means for maintaining the parts cool. 35 Where only the latter effect is desired the water may circulate through the channels and chambers under its own pressure, and, if desired, without the use of valves. The air and gas are drawn into each end of the compression-cylinder B, as the piston B' moves longitudinally through a valve, V, hereinafter de- 40 scribed, and the mixture is compressed on the return motion of the piston until a channel, a, in the latter is brought into communication with a port, 4 or 5, leading to that end of the cylinder A toward which the piston B' is moving. The mixture is thus compressed and then delivered suddenly to the explosion-cylinder shortly after the piston D has begun its movement from the port through which the mixture is delivered, as described in my application for Letters Patent filed August 10, 1882. 45 This engine illustrated differs from that described in said application in being double-acting. The piston B' therefore has two channels, a a', one extending from each end to the side, as shown in full and dotted lines, Fig. 2, and one above the other, and there is no other passage for gases through the piston. The mouth of the port 4 in the cylinder B is on 50 a level with the channel a', as shown in Fig. 4, and the mouth of the port 5 is on a level with the channel a, as shown in Fig. 3, and in each is a check-valve, b. By this construction a charge of compressed gases is delivered 55 to each end of the working-cylinder at each stroke. The reduction of the quantity of gases drawn into the cylinder B in proportion as the speed of the engine is increased is effected by opening a circulating-channel, 8, as 60 the speed increases, thereby causing the gases to circulate from end to end and decreasing the amount drawn in, as described in my aforesaid application. The channel 8 is 65 opened and closed by a valve, 9, controlled by the governor. For many purposes, especially when the engine is used for pumping, where a sudden pressure against a body of incompressible fluid would result in strains, it is 70 very desirable to impart a gradual action to the piston. I effect this in the engine shown by the construction of the cylinder A and piston D, so as to explode a comparatively small volume of explosive gases against the piston in a comparatively large chamber. 75 Thus, as the piston D begins to move from either end of the cylinder A—say from the left—the plunger d separates the chambers F and E, the explosive gases flow through the port 4 into the chamber E, and air is drawn 80 into the chamber F through a port, G, in which is a check-valve, L. The igniting-port 85

e is so situated that it will be uncovered about the time that the plunger d leaves the chamber F, putting the chambers F and E into communication, so that the explosion of gases occurs in front of a body of air which is practically unmixed with said gases and affords a yielding cushion therefor, but which, being heated by the gases, expands gradually and insures the motion of the piston with less of a shock than results from the explosion of the entire contents of the chamber. The parts may be set so as to permit a slight communication between the two chambers just before the explosion, and other structures and valve arrangements may be used, so as to put the explosion-chamber into communication with another chamber containing a body of non-explosive gas just prior to or after the explosion, the effect being approximately the same, and by thus varying the structure and arrangements I can adapt the machine to the special class of work to be performed. As there are two chambers, there should be two outlets for the spent gases. I therefore put the exhaust-pipe P into communication with the chamber F by a channel, h, and the port G, and with the chamber E by a channel, h', fitting valves o o' to seats in said channels, both valves being connected to one stem, N, a spring, f, tending to keep the valves normally on their seats. As one valve counterbalances the other, the automatic lifting of the valves under the back-pressure is prevented. To lift the valves as the piston begins its return movement, I use a tappet, M, upon the cross-head O, which strikes and tilts a T-lever, R, as the piston completes its stroke in either direction, said lever being slotted to receive a pin, i, on a lever, X, arranged below the valve-stems N N, and lifting first one and then the other as the lever R is vibrated. The movement of the piston-rod is communicated to a crank-shaft through the medium of a pair of connecting-rods, an eccentric operating the piston B; but any other devices may be used for these purposes. The arresting of the engine with a full charge in the cylinder, ready to be exploded to start the engine, is effected by forming a triangular link, I, upon the eccentric-rod J to receive the cross-pin j of the connecting-arm B². When the link is down the piston B' reciprocates with the movement of the eccentric in unison with the main piston. When the link is raised the piston B' is left in position and the motion of the eccentric is without effect, substantially as described in my application executed September 16, 1882. The air and gas inlet valves V consist each of a disk-valve, k, fitted to a seat in the end of the cylinder, and secured to a stem, l, sliding in a bracket, m, and surrounded by a spring, n, which tends to keep the valve in its seat. The gas-pipe p, closed at the end, terminates near the valve-disk, and has a side opening, 11, which is covered by a plate, s, at-

tached to the valve, and having a hole, 29, which communicates with the opening 11 when the valve is off of its seat. When the piston B' moves inward the valve is lifted by the air-pressure and the openings 11 and 29 are made to coincide, so that the gas mingles and enters the cylinder with the inflowing air. When the valve closes, on the piston ceasing its motion, the opening 11 is covered and the flow of gas arrested.

It will be apparent that some of the features above described are applicable to single-acting engines, and to engines of a different construction from that described.

I reserve for other applications for Letters 80 Patent any patentable features not specifically claimed.

I claim—

1. The combination, in a gas engine, of a cylinder and piston and a supplemental chamber, 85 and appliances, substantially as described, whereby said chamber is filled with air prior to the explosion of the charge, and is put into communication with the explosion-chamber at about the moment of the explosion, substantially as set forth.

2. The combination of the explosion-chamber, a supplemental air-chamber communicating with the end thereof, and appliances, substantially as described, whereby mixed gases 95 are exploded in the explosion-chamber against a body of air in the supplemental chamber, substantially as set forth.

3. The combination, with the cylinder, of a piston having a plunger-extension, inlet and 100 exhaust ports and channels, valves o o', levers X and R, and tappet upon the piston-rod, substantially as set forth.

4. A gas-engine having a piston for acting directly on a body of water, and provided with 105 a chamber for containing a body of air, and appliances, substantially as described, whereby said chamber is put into communication with the explosion-chamber about the time of the explosion, substantially as set forth.

5. The combination, with the double-acting explosion-cylinder and its piston, of the compression-cylinder B, having gas and air inlets at the ends, piston B', having ports a a', extending from opposite ends to the side, and 110 ports 4 5 between the two cylinders, substantially as specified.

6. The combination, in a gas-engine, of a hollow piston and piston-rod and a pump-cylinder and check-valves, whereby water is drawn 115 into and forced positively from said piston and through the rod by the reciprocating of the latter, substantially as set forth.

In testimony whereof I have signed my name to this specification in the presence of two subscribing witnesses.

CYRUS W. BALDWIN.
